UNITED STATES PATENT OFFICE.

ORVILLE M. KNOX, OF ONEIDA, NEW YORK.

WIRE FENCE.

SPECIFICATION forming part of Letters Patent No. 544,509, dated August 13, 1895.

Application filed December 17, 1894. Serial No. 532,019. (No model.)

To all whom it may concern:

Be it known that I, ORVILLE M. KNOX, of Oneida, in the county of Madison, in the State of New York, have invented new and useful 5 Improvements in Wire Fences, of which the following, taken in connection with the accompanying drawings, is a full, clear, and exact description.

This invention consists in improved means 10 of stretching and securing fence-wires to the posts of a fence, all as hereinafter more fully described, and specifically set forth in the claim.

In the annexed drawings, Figure 1 is a front 15 view of a section of a wire fence embodying my invention. Fig. 2 is an enlarged front view of a section of the main fence-post to which the wire-stretchers are attached, a portion of the detachable plate being broken 20 away to show more fully one of the mortises and sockets formed in the post. Fig. 3 is a side view of the same. Fig. 4 is an enlarged face view of a section of one of the intermediate stays of the fence, and Fig. 5 is a trans- 25 verse section on line X X in Fig. 4.

P represents the main stationary fence-post from which the fence-wires *t t t* are stretched. For this purpose I pivot to said post the winches *a a* and secure the aforesaid wires 30 thereto. The winch I prefer to form with an eye extending transversely through it, and through this eye passes the end of the wire, which is bent over onto the shaft of the winch, so as to tie the wire thereto. I preferably se- 35 cure the winches to the post P by forming in the face of the latter the mortises *c c*, extending across the post, as more clearly shown in Fig. 2 of the drawings. In one end of the vertical wall of the mortise is formed the 40 socket or journal-bearing *a*, which is preferably of the form of a notch extending through the end of the mortise. The mortise is of a size to crutain the shaft of one of the winches with wire wound thereon.

To the face or front of the post P is secured 45 a plate C by means of screws or other suitable fastening devices. Said plate may be of either iron or steel or wood and is provided in one of its edges with the notches or jour- 50 nal-seats *c' c'*, which are axially in line with

the journal-bearings *d d*, and in these bearings are mounted the journals of the winches.

Each of the winches is formed with a square or polygonal outer end for the application of the wrench by which to turn the winch, and adjacent to said portion of the winch is a disk *e* formed integral with the winch-shaft. This disk is of such a diameter as to cause a portion of its periphery to project from the post, and near the edge of the disk are perforations 60 for the reception of the locking-pin *l*, which is removably inserted in one of said perforations and projects from opposite sides of the disk, so as to come in contact with the side of the post and thereby prevent the winch from being turned by the tension of the wire *t* attached thereto.

In tightening the wire the pin *l* is removed, and by means of a wrench applied to the winch the latter is turned to wind the wire 70 thereon, and when the necessary tension is applied to the wire the pin *l* is inserted in the disk *e*, and thus the winch is locked on the post.

To brace the post P, so as to effectually re- 75 sist the strain from the wires *t t*, the auxiliary post *P'* is firmly set into the ground a short distance from the main post P, and between these posts, near the upper ends thereof, is interposed the gas-pipe or tubular metallic 80 strut *f*. A twisted wire *h* is extended diagonally from the lower portion of the post P to the upper part of the auxiliary post and passes through holes bored through the two posts and is firmly tied to said posts. 85

D D represent the intermediate stays, sometimes termed "floating-posts," which are employed to maintain the wires at the requisite distances apart and prevent live stock from forcing their way through the fence. These 90 stays are of the form of slats and may be composed of either metal or wood. To secure them to the wires *t t*, I prefer to provide the stays with perforations *i i* and employ the wire ties *r*, each of which I bend into a loop 95 *r'* in the center of its length. By placing said loop astride the wire *t* and passing the end portions of the tie *r* through the perforation *i* said loop is made to embrace the wire *t*, and then by bending said end portions in opposite 100

directions across the stay D and twisting the ends around the fence-wire t, adjacent to the edges of the stay, the latter is firmly secured to the fence-wire, as clearly shown in Figs. 4 and 5 of the drawings.

What I claim as my invention is—

In a wire-fence, the combination of the post —P— having mortises —c—c— extending across the side thereof and provided in the vertical face of each mortise with a socket —d— extending through one end of the mortise, the plate —C— secured to the mortised side of the post and provided in its edge with the journal-seats —c'—c'— axially in line with the aforesaid sockets, the winches —a—a—

disposed in the mortises —c—c— and having their journals mounted in the aforesaid sockets and seats, the wires —t—t— secured to said winches, the disks —e—e— integral with the winches and perforated near their outer edges, and locking-pins —l—l— inserted removably in the perforations of the disks as set forth.

In testimony whereof I have hereunto signed my name this 26th day of November, 1894.

ORVILLE M. KNOX. [L. S.]
